UNITED STATES PATENT OFFICE.

JOHN F. STEVENSON, OF TOWER HILL, OHIO.

WEATHER-STRIP.

1,151,973.

Specification of Letters Patent. Patented Aug. 31, 1915.

Application filed December 2, 1912. Serial No. 734,468.

To all whom it may concern:

Be it known that JOHN F. STEVENSON, a citizen of the United States of America, and resident of Tower Hill, county of Hamilton, and State of Ohio, has invented certain new and useful Improvements in Weather-Strips, of which the following is a specification.

This invention relates to weather strips and particularly to strips which are capable of being moved to operative positions, when the doors or windows to which they are secured are moved to closed positions.

An object of this invention is to produce an improved weather strip for swinging doors or windows, which is capable of producing a weather-tight joint between the door or window and its stationary or supporting frame. This and other objects I attain by means of a strip embodying the features herein described, and illustrated in the drawings accompanying and forming a part of this application.

In the drawings Figure 1 is a fragmental vertical sectional view of a door and door sill, and illustrates an embodiment of my invention moved to the sill-engaging position. Fig. 2 is a view corresponding to Fig. 1, except that the door is not in the closed position and the strip shown as an embodiment of my invention is moved to a position out of engagement with the stationary sill. Fig. 3 is a fragmental vertical elevation of a swinging window equipped with a strip embodying my invention, the window being shown in the closed position, relatively to its stationary supporting frame. Fig. 4 is a view corresponding to Fig. 3 and illustrates the window swung to a partially open position, relatively to the stationary supporting frame, and the weather strip moved to a position in which it clears the frame.

The illustrated embodiment of my invention consists of a hinged strip 5, which is mounted on the outside of a swinging door or window sash, and is adapted to move across and to engage a vertical face of the sill or a corresponding stationary member, when the door or window, to which it is secured, is moved to the closed position.

In Figs. 1 and 2 I have shown an embodiment of my invention which is particularly adapted to be employed on a swinging door, and as illustrated, includes a Z-bar 6, which is secured to the outside of the door near its lower edge, and the weather strip 5, which

is mounted on the Z-bar by means of a hinge 7, and is capable of being moved—when the door is closed—from a substantially horizontal position, as shown in Fig. 60 2, to a substantially vertical position, as shown in Fig. 1, in which it engages a vertical face of a stationary member 8, across which it moves during the operation of closing the door. In Figs. 1 and 2, the stationary member referred to, is the door sill

and the weather strip is so constructed that it moves into engagement with the outer vertical face of the sill when the door is closed. The strip 5, as illustrated, consists 65 of a channel iron and it is actuated by means of a shiftable member 9, through the agency of a link 10 and a bolt 11, which is provided with an arc-shaped head. The member 9, as illustrated in Figs. 1 and 2, is mounted in a 70 way or guide 12, which is mounted on the door 13 and is located at or near its lower edge. One end of the member 9 is pivotally secured to the link 10 and the other end is provided with a down-turned head or projection 14, which is adapted to engage the inner vertical face of the sill 8, during the 75 operation of closing the door and which operates to move the member 9 inwardly, relatively to the door, and to thereby swing 80 the strip 5 from a horizontal to a vertical position, in which, as has been said, it engages the sill. The member 9 and the link 10 are so constructed and located with reference to the strip 5, that the strip 5 assumes the vertical position and engages the 85 sill when the door 13 is moved to the fully closed position. A spring 15 is provided 90 for actuating the member 9 to move the strip 5 to the horizontal position. As illustrated, a coil spring is employed, and it is located between a shoulder formed on the member 9 and the inner end of the guide 12. The lower end of the guide is slotted, so 95 that the head 14 moves, in response to the pressure of the spring, to a position intermediate the inner and outer faces of the door, on which it is mounted, when the door is opened. With this construction the member 9 is invisible from the inside of the door, 100 when the door is open and is not conspicuous enough to be unsightly when the door is closed. The Z-bar 6, as illustrated, extends 105 transversely across and parallel to the lower edge of the door on which it is mounted, 110 and it is so located that its projecting flange extends downwardly and the channel iron

or strip 5 is secured to the downwardly projecting flange by means of the hinge 7. The strip or channel 5 is turned so that its flanges project downwardly when the strip is in the horizontal position and inwardly when it is in the vertical position, and it is so mounted that the outer end of the channel travels through a relatively long path and is lifted a relatively large amount during the operation of turning the channel from the vertical to the horizontal position. This is accomplished by so locating the hinge, relatively to the strip, that the pivotal point of the strip is located nearer the upper or inner edge than the lower or outer edge of the strip. The bolt 11, to which the link 10 is secured, is so located, relatively to the pivotal point of the hinge, that the lower edge of the hinge will be swung upwardly to a position clear of the top face of the sill for a slight opening movement of the door or a slight movement of the member 9. The rounded head of the bolt is also so formed that it will aid the member 14 in moving or holding the strip 5 in the horizontal position during the operation of opening the door. This is accomplished by so proportioning the bolt that its rounded or arc-shaped head will engage and ride across the sill during the operation of opening the door, if the member 9 has for any reason failed to move the strip 5 to its horizontal position. During the operation of closing the door, the strip 5 is held in the horizontal position, by the spring 15, until after the head 14 engages the inner vertical face of the sill, and the outer edge of the strip moves clear across the top of the sill before the strip is turned from the horizontal position. When the door is almost closed the head 14 engages the sill and is moved from the position shown in Fig. 2 to the position shown in Fig. 1, by the further closing of the door, and when the door is fully closed, it operates through the agency of the link and the bolt 11 to hold the lower or outer flange of the strip or channel iron 5 in contact with the outer vertical face of the sill. This forms a substantially weather-tight joint and absolutely prevents water from running down the outer surface of the door and through the crack between the door and the sill. In opening the door, the head 14 of the member 9 is released from the sill and the spring 15 shifts the member 9 outwardly, relatively to the door, and swings the strip to the horizontal position, in which it clears the sill.

In Figs. 3 and 4 I have shown an embodiment of my invention which may be employed with an inwardly swinging French window 16. The strip 5 is similar to the strip illustrated in Figs. 1 and 2 and it is mounted by means of a hinge 7 on a Z-bar 6, the projecting flange of which is turned downwardly. The Z-bar extends trans-

versely across the window sash and is located near its lower end. The actuating member of the strip consists of a hollow tubular member 17, which is located within and is movable longitudinally along a sleeve or way 18, which projects through a transversely extending aperture provided near the lower edge of the sash of the window. A coil spring 19 is located between an abutment, provided at the inner end of the sleeve 18, and the head portion of the tubular member 17, and is adapted to move the member 17 to the position shown in Fig. 4, in which it holds the strip 5 in a horizontal position, through the agency of the link 10 and the bolt 11. In Figs. 3 and 4, an angle iron 21 is mounted on the window sill and forms an abutment against which the window sash contacts when the window is in the closed position. As illustrated, the projecting flange of the angle iron 21 extends upwardly beyond the lower edge of the sash and is provided in its upper edge with a notch 22. The sleeve 18, and consequently, the tubular member 17, are so located on the window sash that the outer end of the tubular member engages the projecting flange of the angle iron 21 at a point immediately adjacent to the notch 22, during the operation of closing the window and the notch receives the link 10 when the window is closed and the strip 5 is in the vertical position. When the strip is in this position the rounded head of the bolt 11 is located on the outside of the projecting flange of the iron 21 in such a position that it will aid the tubular member 17 in swinging the strip from the vertical to the horizontal position, by riding over the upper edge of the flange during the operation of opening the window. The spring 19, however, normally tends to hold the tubular member 17 in the projecting position, shown in Fig. 4 and consequently tends to move the strip to the horizontal position. During the window closing operation the head portion of the tubular member 17 contacts with the angle irons 21 and is moved into the sleeve 18, in which position it compresses the spring 19 and holds the strip 5 in a vertical position, with its lower flange in engagement with the outer face of the upwardly projecting flange of the iron 21. In other respects the operation of the strip shown in Figs. 3 and 4 is substantially similar to that of the strip shown in Figs. 1 and 2 and the upwardly projecting flange of the angle iron 21, corresponds to the sill 8, in its coöperation with the strip. The hinges employed in mounting both of the strips 5 may be located near the ends of the strips, and various means may be employed for mounting the strips on the doors or windows, with which they are employed. By employing the link 10

between the strip and its actuating member, a more substantial device is obtained than has previously been procured, and the construction of the strip and its actuating mechanism is materially simplified and its 5 operation is rendered more positive.

It will be understood that, while the strip is illustrated in Figs. 3 and 4, in the position for closing the joint between the 10 lower edge of the window, that it may be employed with equal success for closing the joints between the other edges of the sash and the window frame, and that various changes, modifications and substitutions 15 may be made in the device illustrated without departing from the spirit and scope of my invention as set forth by the appended claim.

What I claim is:

20 In combination with a stationary abutment, a swinging member capable of being moved to an open or a closed position, with relation to the abutment, a

weather strip hinged on said member, a shiftable member mounted within the 25 swinging member and capable of being engaged by said abutment, a link pivotally secured to the shiftable member, a bolt having a rounded head mounted on the shiftable member and to which said link is 30 pivotally secured, said bolt being so mounted that its rounded head engages said abutment and aids in the movement of said strip to a position clear of the abutment, and a spring located within the swinging 35 member and the shiftable member, for engaging the shiftable member and for thereby swinging the strip to a position clear of the abutment.

In testimony whereof, I have hereunto 40 subscribed my name this 30th day of November, 1912.

JOHN F. STEVENSON.
